United States Patent

Des. 241,716
Patented Oct. 5, 1976

241,716

BOTTLE OR SIMILAR ARTICLE

Livingston C. Douglas, Leonia, N.J., assignor to Colgate-Palmolive, New York, N.Y.

Continuation-in-part of design application Ser. No.
292,977, Sept. 28, 1972, which is a continuation-in-part of design application Ser. No. 246,517, Apr. 21, 1971.
This application Oct. 9, 1973, Ser. No. 404,447

Term of patent 14 years

Int. Cl. D9—01

U.S. Cl. D9—125

FIG. 1 is a side elevational view of a bottle or similar article embodying my new design;

FIG. 2 is a top plan view; and

FIG. 3 is a bottom plan view thereof.

This application is a continuation-in-part of Ser. No. 292,977 filed Sept. 28, 1972 which is a continuation-in-part of Ser. No. 246,517 filed Apr. 21, 1971.

I claim:

The ornamental design for a bottle or similar article, as shown and described.
